UNITED STATES PATENT OFFICE.

JOSEF DORNBUSCH, OF CREFELD, GERMANY.

DESIGN FOR BOX-COVER PAPER OR SIMILAR ARTICLE.

Application filed April 26, 1926. Serial No. 17,448. Term of patent 7 years.

To all whom it may concern:

Be it known that I, JOSEF DORNBUSCH, a citizen of Germany, residing in the city of Crefeld, in the Republic of Germany, have invented a new, original, and ornamental Design for Box-Cover Paper or Similar Article, of which the following is a specification, reference being had to the accompanying drawing, forming part thereof, which illustrates a face view of a piece of box-cover paper or similar article, embossed with my new design.

I claim—

The ornamental design for box cover paper or similar article, as shown.

JOSEF DORNBUSCH.
